UNITED STATES PATENT OFFICE.

SIMON DUBINSKY, OF BONNE TERRE, MISSOURI, ASSIGNOR OF ONE-HALF TO MAX BROIDA, OF ST. LOUIS, MISSOURI.

SAFETY-POCKET FOR GARMENTS.

1,239,578.

Specification of Letters Patent. Patented Sept. 11, 1917.

Application filed April 12, 1917. Serial No. 161,516.

To all whom it may concern:

Be it known that I, SIMON DUBINSKY, a citizen of the United States, residing at Bonne Terre, St. Francois county, Missouri, have invented a certain new and useful Improvement in Safety-Pockets for Garments, of which the following is a full, clear, and exact description, such as will enable others skilled in the art to which it appertains to make and use the same, reference being had to the accompanying drawings, forming part of this specification.

My invention relates generally to garments or wearing apparel, and more particularly to a pocket therefor, the principal object of my invention being to combine with an ordinary garment pocket a safety or thief-proof pocket, the entrance into which is concealed and arranged so that it cannot be readily found by a person unfamiliar with the construction of the entire pocket.

By virtue of my improved construction it is possible for the wearer of the garment provided with the pocket to carry his money and valuables with a comparatively high degree of safety by reason of the fact that it is practically impossible for a thief or pickpocket to gain access to the safety pocket.

A further object of my invention is to provide a safety pocket which is comparatively simple in construction and which can be readily combined with any ordinary pocket, and said safety pocket being entirely hid from view and occupying little, if any, space.

With the foregoing and other objects in view, my invention consists in certain novel features of construction and arrangement of parts, hereinafter more fully described and claimed, and illustrated in the accompanying drawings, in which—

Figure 1 is an elevational view of a pair of trousers and showing my improved safety pocket combined with the hip pocket of said trousers;

Fig. 2 is an enlarged vertical section taken approximately on the line 2—2 of Fig. 1;

Fig. 3 is a cross section taken approximately on the line 3—3 of Fig. 2.

Referring by numerals to the accompanying drawings, 10 designates the garment fabric in which the usual pocket opening 11 is formed. The edge of the material imme-

diately above this opening is folded inwardly and upwardly, and said folded edge is secured to the body of the goods 10 in any suitable manner, preferably by a row of stitching 12, the same being arranged immediately above and parallel with the opening 11.

Positioned against the inside of the fabric 10 and immediately above the pocket opening is a facing strip 15, preferably of fabric, the same overlying the inwardly turned edge of said fabric 10 and being secured thereto by the row of stitching 12. Secured to this facing strip 15 by the row of stitching 12 is a depending flap 16, preferably of fabric, the same extending a substantial distance below the pocket opening 11 and secured to the rear side of the upper portion of this flap by the row of stitching 12 is the upper edge of a section of fabric 17 which forms the inner wall of the inner or primary pocket of the garment. This fabric extends a substantial distance below the pocket opening 11 and then extends upward as designated by 18 to form the outer wall of the primary pocket. The upper portion of this outer wall 18 passes through the pocket opening 11 and extends from said opening downward as designated by 19, said downwardly extending portion forming a lining for a flap 20, the latter being preferably formed of the same fabric or goods of which the garment is formed and said flap being secured to the lining in any suitable manner, preferably by means of rows of stitching 21.

The ends of the flap 21 and the portion 19 of fabric section 16 are secured to each other and to the fabric 10 at points below the ends of the pocket opening 11 by vertically disposed rows of stitching 22.

Secured to the lower portion of the outer wall 18 of the inner or primary pocket, preferably by stitching, is the lower end of a section of fabric 23, the same extending upward parallel with the wall 18, said section of fabric forming the outer wall of an intermediate or secondary pocket, the mouth or opening into which is beneath the flap 20.

Secured to the inside of the fabric 10 immediately below the pocket opening 11 is one edge of a strip of fabric 24, the same lying immediately beneath the flap 20 and its lining 19, and the body of said strip is folded downwardly as designated by 25, thus form-

ing a flap for the safety pocket and which flap lies between the upper portions of walls 18 and 23.

If desired, a fastening device 26 of the ball and socket type may be utilized between the depending edge of flap 25 and the upper edge of wall 23, although such fastening is not absolutely essential.

Secured to the lower edge of flap 25 is one edge of a fabric section 27, the same lying immediately against the member 24 and extending downward between the fabric section 23 and the goods 10 of the garment below the pocket opening 11, said fabric section 27 forming the outer wall for the outer or safety pocket, and the lower end of said fabric section is secured to the lower portion of section 23.

It will be understood that the side edges 20 of fabric sections 17, 18, 23 and 27 are secured together in any suitable manner, preferably by means of rows of stitching 28 and the space *a* between the walls 17 and 18 constitutes the primary or inner pocket; the 25 space *b* between the walls 18 and 23 constitutes the secondary or intermeditae pocket, and the space *c* between the walls 23 and 27 constitutes the third or safety pocket.

Access is gained to primary pocket *a* 30 through the mouth or opening 11 at the upper end of said pocket and access is gained to the secondary pocket *b* by raising the central portion of flap 19 and then passing the hand downward between flap 25 and upper 35 portion of wall 18.

To gain access to the third or safety pocket it is necessary to raise flap 20 and then raise flap 25 which is reversely positioned with respect to said flap 20. Thus, a person unfamiliar with the construction of the pocket and attempting to pick the same, might insert his hand in the primary pocket or even in the secondary pocket, but the flap 25 overlying the mouth of the safety pocket 40 effectively closes the opening thereto and reduces to a minimum the chances of said pocket being found and entered.

A safety pocket of my improved construction is comparatively simple, can be readily

manufactured and combined with an ordinary garment pocket, and said safety pocket provides means whereby money and valuables may be carried without danger of their being taken by pickpockets and the like.

It will be readily understood that minor changes in the size, form and construction of the various parts of my improved safety pocket can be made and substituted for those herein shown and described, without departing from the spirit of my invention, the scope of which is set forth in the appended claims.

I claim:

1. A garment having a pocket opening, 65 pocket walls depending from said opening, one of which walls is provided at its upper end with a flap which extends outwardly through and downwardly from the pocket opening, a third pocket wall arranged parallel with the first mentioned pocket walls and secured at its lower portion to one of the latter, and the upper end of said third pocket wall being folded downward over the upper edge of one the first mentioned pocket walls 70 to form a flap which is arranged beneath and oppositely disposed relative to the first mentioned flap.

2. A garment provided with a pocket opening, walls depending from said opening and disposed so as to form three pockets, one of which walls is provided with a depending flap which extends through and downwardly from the pocket opening, another one of said walls being provided at its upper edge with a flap which is arranged beneath and oppositely disposed with respect to the first mentioned flap, and said second flap extending into the mouth of one of the pockets so as to close the mouth of 85 another one of said pockets.

In testimony whereof I hereunto affix my signature in the presence of two witnesses, this 24th day of March, 1917.

SIMON DUBINSKY.
